SEMIAUTOMATIC APPARATUS FOR
SPRAYING OIL ON ARTICLESEugene L. Malhiot, Maywood, Ill., assignor to
Western Electric Company, Incorporated, New
York, N. Y., a corporation of New York

Application May 22, 1947, Serial No. 749,814

6 Claims. (Cl. 91—45)

1
This invention relates to apparatus for spraying articles and more particularly to an apparatus for oiling telephone equipment banks.

It is an object of the present invention to provide a simple apparatus for efficiently and effectively spraying articles.

In one embodiment of the invention, step by step telephone system banks are placed on a supporting plate in a row between a pair of guide rails and moved against a stop member, which positions an intermediate one of the banks in the row over an aperture in the plate, where it is adapted to receive a charge of oil in the form of a mist projected upwardly from an oil spray gun mounted below the aperture. An electrical control mechanism, including a switch, which is actuated by the movement of the banks against the stop member, causes the oil gun to spray a predetermined amount of oil upwardly through the aperture onto the bank located directly thereabove. After the intermediate one of the row of banks disposed above the aperture has been oiled, the previously oiled bank at the leading end of the row may be removed and an unoiled bank added to the other end of the row and advanced to move the row against the stop member, thereby positioning an unoiled bank over the aperture and actuating the control mechanism to effect the oiling of said last-mentioned bank.

The invention will be more fully understood from the following description when considered in connection with the accompanying drawings illustrating a preferred embodiment thereof in which.

Fig. 1 is a fragmentary plan view of the apparatus with parts in section;

Fig. 2 is a vertical sectional view of the apparatus taken on the line 2—2 of Fig. 1 and showing, in dot and dash lines, a row of banks in position on the apparatus;

Fig. 3 is a vertical sectional view of the apparatus taken on the line 3—3 of Fig. 2 and indicating a bank thereon in dot and dash lines;

Fig. 4 is a vertical detail cross sectional view taken on the line 4—4 of Fig. 1 and showing a bank in full lines thereon;

Fig. 5 is a diagrammatic view of the spray gun with its oil supply and air connections thereto and the electrical control circuit for controlling the operation thereof.

The apparatus herein illustrated, comprising one embodiment of the invention, is designed to oil the wiper ends 10 of terminal members 11 on telephone equipment banks 12. The banks 12 are subjected to an oil spray before being assembled

into larger units of telephone equipment. Each bank comprises a plurality of arcuately shaped card units on which the terminals 11 are mounted, with the wiper ends thereof extending radially inwardly, and the card units are clamped together between end clamping plates by a plurality of clamping posts.

The oiling apparatus comprises a supporting table or plate 21 suitably mounted in a bench top 10 22 (Fig. 2), which table is provided with a rectangular aperture 24. The aperture 24 is of such a size as to unmask or expose the wiper ends 10 of all of the terminals of a bank 12 placed thereabove. The banks 12 are adapted to be placed 15 on the table 21 side by side in a row with the wiper ends 10 of the terminals directed downwardly, as indicated in Fig. 4, and successively moved into position above the aperture 24, in which position they receive a charge of oil spray. 20 A pair of rails 26 and 27 are secured to the upper side of the table 21 on opposite sides of the aperture 24 and, together with the plate, form a guideway to position the banks 12 endwise relative to the aperture and to guide the banks for movement on the apparatus. Semi-cylindrical blocks 28 and 29 are mounted on the upper surface of the plate 21 adjacent the aperture 24 to form vertical extensions of the opposite wall portions of the aperture to conform generally to the arcuate underside of the banks 12.

A spray gun 32, disposed in vertical alignment with the vertical axis of the aperture 24, is mounted below the plate 21 on a bracket 34 depending therefrom and is connected by a conduit 35 (Fig. 5) to an oil supply 36 and by the conduit 37 to a source of compressed air admitted to the spray gun 32 under control of a solenoid operated valve 39. The solenoid operated valve 39 is actuated under control of an electrical circuit including a switch 41, which is mounted on the upper side of the plate 21 in the path of movement of the banks 12. The switch 41 is spaced from the aperture 24 so that when a row of banks 12, placed on the table between the guide rails 26 and 27, is moved into engagement therewith, the switch will be actuated thereby and will also stop them in a position so that one of the banks is located above and in alignment with the aperture 24, as indicated in Fig. 2. The switch 41 may thus act as a stop for the row of banks 12, but preferably a stop member 43, in the form of an angle member, is secured to the plate 21 to stop the banks 12 on the table in a position to properly align one of them with the aperture 24. A semi-cylindrical casing or hood 45 is positioned over

the portion of the apparatus immediately above the aperture 24 and it is connected, through a rearwardly extending portion 46 and a conduit 47, to an exhaust system, not shown, for exhausting the excess oil fumes. A casing 49 is secured to the under side of the plate 21 and encloses the spray gun 32 for receiving the oil which might accumulate during the operation of the apparatus and which oil may be drained therefrom through a valve 50 mounted on the lower portion of the casing 49.

In the apparatus, space is provided between the stop member 43 and the hood 45 greater than the width of the bank 12 so that the oiled bank at the leading end of the row of banks moved into engagement with the stop 43 is accessible and may be removed by the operator on completion of the cycle of operation. The rail 27 is, accordingly, terminated at 49 in spaced relation to the stop 43 to permit the oiled end bank to be removed from the apparatus by sliding it forwardly. With the foremost bank removed from the row, an unoiled bank may be added to the lefthand end of the row and moved to the right to advance the row of banks against the stop 43. This movement of the row of banks will position an unoiled bank above the aperture 24 and also cause the actuation of the switch 41. The actuation of the switch 41, through the control circuit, will cause the spray gun 32 to discharge a predetermined amount of oil in the form of an oil spray upwardly through the aperture 24 onto the lower portion of the bank located immediately above it. This cycle of operation may be continued until the desired number of banks has been oiled.

The switch 41 in the control circuit is of the single pole, double-throw type, in which the pole 52, which is connected to a line 53 of a pair of power lines 53 and 54, normally engages the contact 56 and is movable out of engagement therewith into engagement with the contact 57 when the switch 41 is actuated by the movement of the row of banks 12. The contact 56 is connected to one end of the winding 58 of a slow-to-operate solenoid type relay 59, the other side of the winding of which is connected to the power line 54. Contact 57 of switch 41 is connected to the movable contact member 61 of the relay 59 and when the circuit to the coil 58 is closed, as shown in Fig. 5, coil 58 is energized and acts, through linkage 60, to move the contact member 61 out of engagement with a contact 62 of the relay 59. The contact 62 is connected to a movable contact member 63 of a solenoid type slow-to-operate relay 64 and also to one side of the winding of the coil 65 of the relay 64, the other side of the winding of the coil 65 being connected to power line 54. The contact member 63 is normally in engagement with contact 67 of relay 64 and contact 67 is connected to one side of the winding 70 of the solenoid actuated valve 39, the other side of the winding of which is connected back to the line 54.

When the row of banks is moved to actuate the switch 41, the pole 52 is moved from engagement with the contact 56 into engagement with the contact 57, which movement of the pole 52 breaks the circuit to and deenergizes coil 58 which, in turn, effects the movement of the contact member 61 to a position in engagement with the contact 62. A circuit is thereby completed from the line 53, through the switch 41, contact member 61, and contact 62 of relay 59, to the contact member 63 of relay 64 and through the coils 65.

and 70, connected thereto in parallel, to the line 54. On completion of the power circuit to the coil 70, the coil is energized to actuate the valve 39 and cause the gun 32 to project a spray of oil upwardly, as previously described. The relay 64, as previously stated, is of a slow-acting type so that the coil 65 thereof operates after a predetermined time interval to disengage the movable contact 66 from the contact 67 to open the circuit to the coil 70 of the valve 39 and terminate the operation of the spray gun 32. Thus the slow-acting relay 64 controls the duration of the operation of the oil gun 32 and serves, after actuation, to maintain the circuit to the coil 70 open until the circuit to the relay 64 is opened through the switch 41 by the removal of the bank 12 engaging it. With the removal of the bank, the switch 41 is restored to its normal position which, in turn, restores the relays 59 and 64 to their normal operating condition, as indicated in Fig. 5. The relay 59, as previously stated, is of the slow-acting type, which imposes a predetermined time delay before its operation for the purpose of avoiding any fluttering movement of the movable contact member 61 due to the inadvertent opening and closing of the switch 41 during the removal of the bank 12 from the apparatus.

It will be apparent, from the above description, that with the above-described apparatus, an unoiled bank may be added to the row of banks in the apparatus and moved in a predetermined direction to initiate the operation of the spray gun to spray a bank, after which an oiled bank may be removed from the apparatus.

What is claimed is:

1. An apparatus for spraying articles comprising a guideway for supporting a plurality of articles in a row and for guiding said articles for movement in a predetermined path of travel, means for stopping said row of articles in a predetermined position on said guideway, said guideway being formed with an aperture therein to expose predetermined portions of the articles arranged in said row, a spray gun mounted in alignment with said aperture for projecting a spray therethrough onto the articles exposed by said aperture, and control means operable in response to the movement of one of said row of articles and the engagement of the foremost article in said row with said stop means for causing said spray gun to direct a predetermined amount of spray through said aperture, said guideway being arranged to permit sprayed articles to be removed from the forward end of the row and unsprayed articles to be added to the other end of the row and advanced to move the row of articles into engagement with the stop means.

2. An apparatus for spraying articles comprising an apertured guideway for supporting a plurality of articles in a row and for guiding said articles successively over the aperture in said guideway, a stop member on said guideway for stopping said articles in said row in a predetermined position to locate an intermediate one of said articles in alignment with said aperture, a spray gun mounted in alignment with said aperture for projecting a spray therethrough onto the article aligned therewith, a switch operable in response to the movement of said row of articles into engagement with said stop, and means operable in response to the actuation of said switch for causing said spray gun to project a spray through said aperture for a predetermined interval of time.

3. An apparatus for oiling banks comprising an

apertured table for supporting a series of individual banks for movement thereon, members for guiding said banks on said table in a predetermined path over said aperture, an oil gun disposed below said table in alignment with said aperture and operable to direct a spray of oil upwardly through said aperture, a switch mounted on said table in the path of movement of said banks and adapted to be actuated by said banks, means to stop said series of banks in a predetermined position whereby one of the banks is located above said aperture, and electrical control means including said switch for actuating said spray gun to spray oil through said aperture onto the bank positioned thereabove for a predetermined length of time in response to the actuation of said switch.

4. An apparatus for oiling banks comprising an apertured plate for supporting a series of banks thereon, guide members for guiding said banks for movement on said table in a predetermined path over said aperture, a spray head disposed below said plate in alignment with said aperture and operable to direct a spray of oil upwardly through said aperture, a stop member mounted on said plate in the path of movement of said banks at a predetermined distance from said aperture for stopping said banks in a predetermined position on the plate whereby one of the banks is located above said aperture, a switch mounted on said supporting plate adapted to be closed by a bank moved into engagement with said stop member, and an electrical control means including said switch for actuating said spray gun to eject a predetermined amount of oil through said aperture onto the bank positioned thereabove in response to the actuation of said switch.

5. An apparatus for oiling banks comprising an apertured plate for supporting a plurality of banks thereon, guide members for locating said banks in a row and for guiding said banks successively in alignment with the aperture in said plate, a spray gun disposed below said plate in alignment with said aperture therein and operable to project a spray of oil upwardly through said aperture, conduit means through which the oil fumes may be exhausted including a portion mounted on said plate over said aperture and forming a tunnel through which said banks are advanced, a stop member on said plate for stop-

ping said banks in a predetermined position on the plate whereby an intermediate one of said banks in said row is located above said aperture, said stop member being spaced from said tunnel whereby, when said row of banks is moved into engagement with said stop member, the foremost bank is accessible for removal from the apparatus, a switch positioned to be actuated by a bank moved into engagement with said stop member, and an electrical control means operable in response to the actuation of said switch for causing said gun to spray a predetermined amount of oil through said aperture.

6. An apparatus for spraying restricted portions of articles comprising an apertured table for supporting a plurality of articles, means for guiding said articles for movement over said aperture, a spray gun mounted in alignment with said aperture for projecting a spray therethrough onto said articles, a switch actuated by one of said articles when another one of said plurality of articles is in predetermined alignment with said aperture, a power circuit connected to said switch, a solenoid actuated valve connectible to said power circuit for controlling the operation of said spray gun, a first slow-to-act relay normally connected to said solenoid valve and operable in response to the actuation of said relay to disconnect said solenoid actuated valve after a predetermined time interval, a second slow-to-act relay connected to said switch and operable in response to the actuation of said switch to complete the power circuit to said first relay and said solenoid actuated valve whereby said valve is actuated for a predetermined interval of time to cause said spray gun to operate for said predetermined time.
